UNITED STATES PATENT OFFICE.

JOSEPH R. SNEED, OF PULASKI, ILLINOIS.

RAILWAY-TIE.

950,146.

Specification of Letters Patent. Patented Feb. 22, 1910.

Application filed April 7, 1909. Serial No. 488,502.

To all whom it may concern:

Be it known that I, JOSEPH R. SNEED, a citizen of the United States, residing at Pulaski, in the county of Pulaski and State of Illinois, have invented certain new and useful Improvements in Railway-Ties, of which the following is a specification.

This invention relates to railway ties.

The object of the invention is to provide a railway tie of the kind wherein a body of concrete or similar material is molded and has embedded therein metal strengthening rods or plates, which shall be free from the objectionable features possessed by ties of thus character as heretofore made.

With this object in view the invention consists of a railway tie formed and provided with accessories adapting it for continuous use and for detachably connecting rails, having the generic and specific features substantially as hereinafter described and claimed.

The invention is illustrated in the accompanying drawing in which:—Figure 1, is a perspective view of a railway tie constructed in accordance with my invention, rails, in section, being shown in position on the tie; Fig. 2, is a vertical longitudinal sectional view of the tie and means for attaching the rails to the tie; Fig. 3, is a detail view of the means for attaching the cushions to the tie; Fig. 4, is a detail view of the means for attaching the rails to the cushion; and, Fig. 5, is a transverse sectional view of the body of the tie.

In this drawing 1 represents the body of the tie which is of material, preferably concrete, capable of being readily molded when in plastic condition and which will become hard and strong when exposed to air.

In forming the tie each end thereof is indented forming handholds 2, for convenience in handling it.

Formed in the upper face of the tie a short distance from each end is an indentation 3, which is designed to receive and aid in holding in place a supporting block or cushion 4 upon which rails are to be placed and to which the rails are detachably secured. In the bottom of each indentation is a transverse groove 5, the purpose of which will be explained hereinafter.

In the formation of the tie there are suspended in the mold the metal rods 6 and 7 arranged one above the other and which serve to strengthen the tie and also to pro-

vide means of attaching the cushions upon which the rails are to be supported. The rods are each bent at each end at right angles. The rods except the ends thereof are entirely covered by the body of the tie. The ends of the rod 6 extend upward through the inner ends of the respective indentations 3, while the corresponding ends of the rods 7 extend upward through the outer portions of these indentations. The ends of both rods are screw threaded and each is preferably provided with some means which will prevent the displacement by jarring of nuts placed on the screw threads. In the present form I have shown all the exposed ends of the rods as slotted, permitting them to readily be spread after nuts are placed on them and thus to retain the nuts in place. The rods 6 and 7 extend throughout the tie nearly from end to end, and by their form prevent the separation of the parts of the tie should the latter become broken from any cause. As an additional means of strengthening the tie there is incorporated in it one or more wire mesh strips 9, which are entirely inclosed by the material of which the body of the tie is composed, and which are arranged between the rods 6 and 7 and the outer face or faces of the tie.

In order to provide means for securing rails to the tie in a manner to avoid weakening of the tie by the attaching means, and also to prevent shocks or blows from passing trains injuring the tie, there are interposed between the tie and the rails to be supported, the cushions or blocks 4 which may be of wood, compressed paper or other suitable material. The blocks are of a width corresponding to that of the tie, and of a length to fit closely in the indentations 3. Each block has openings through it for receiving one end of each of the rods 6 and 7 and is held in place by nuts placed on the ends of the rods and bearing on the upper face of the block. To lend additional security to the attachment of the blocks I provide plates 12 having downwardly bent ends inclosing the sides of the blocks and having openings receiving the ends of the respective rods. The blocks are of varying thicknesses so that the rails may be raised or lowered by removing a block and substituting another without disturbing the body of the tie and endangering it by changing its position after it is seated. The cushions or blocks are preferably made in two parts as shown, in order

that they may be removed or introduced without displacing the rails.

The rails are attached to the blocks at points over the transverse grooves 5. The cushions or blocks being unsupported at the places of attachment of the rails a more or less elastic or yielding bed for the rails, preventing undue shocks to the tie by passing trains, is furnished.

10 The rails may be attached to the blocks or cushions in any suitable way. For instance, as shown in the embodiment of the invention here illustrated, clips 13 which extend over the flanges of the rails are secured in place by bolts 14 passing through the blocks.

15 The bolts are preferably provided with angular heads, and the openings through which the bolts pass are so located that the heads abut against the sides of the transverse groove and are thereby prevented from turning. The upper ends of the bolts receiving nuts 15 which bear on the clips are preferably split as shown to allow the ends to be spread to lock the nuts in place and prevent 25 their turning.

From the foregoing description it will be clear that by the form of tie described I obtain a support for rails which is capable of long use without displacement, and one which 30 completely insulates the rails held by it. If the rail should become broken there is no possibility of spreading of the rails as the rods will retain the supporting blocks in proper position whatever the condition of the 35 body of the tie. A great advantage which I attain is the facility of removing a supporting block or cushion and substituting another to raise or lower a rail, without necessitating the displacement of the rail.

40 Having thus described my invention, what

I claim as new, and desire to secure by Letters Patent, is;

1. A railway tie of the kind described having rods extending longitudinally therein, each end of the rods being bent at a right angle to the body thereof, and means for connecting the ends to a rail support, substantially as described.

2. A railway tie of the kind described having rods the bodies of which are embedded in the tie, each end of each rod being bent at an angle and extending from the upper face of the tie, means for attaching a rail support to the ends of the rods, and means for attaching rails to the support, substantially as described.

3. A railway tie comprising a body of concrete, strengthening rods embodied in the tie and having each end thereof extending from their bodies at an angle and projecting from the upper surface of the tie, cushion blocks for supporting rails through which the ends of the rods pass, and plates having bent ends inclosing the sides of the cushion blocks, and attached to the ends of the rods, substantially as described.

4. A railway tie comprising a body of concrete having indentations on the upper face thereof, grooves in the bottoms of the indentations, cushion blocks secured in the indentations, and means for attaching rails to the cushion blocks including bolts having angular heads adapted to bear against the faces of the grooves, substantially as described.

In testimony whereof I affix my signature 75 in presence of two witnesses.

JOSEPH R. SNEED.
